UNITED STATES PATENT OFFICE.

L. RICHMOND, OF DERBY, VERMONT.

IMPROVED REIN-GUIDE FOR HARNESS.

Specification forming part of Letters Patent No. 97,814, dated December 14, 1869.

To all whom it may concern:

Be it known that I, LEMUEL RICHMOND, of Derby, Orleans county, in the State of Vermont, have invented a new and Improved Rein-Guide; and I hereby declare the following to be a full and exact description thereof, reference being had to the accompanying drawing, forming part of this specification.

The nature or essence of my invention consists in providing a loop or opening of metal or other suitable material to be secured to the harness for the driving-reins to pass through, in order to prevent their becoming caught or entangled by the horse's tail or otherwise.

The drawing hereinbefore mentioned shows a perspective view of my guide attached to the harness, as seen from the driver's seat.

E is the back-strap of the harness; G, the hip-strap, and H the bottom bar of the guide, secured to the hip-strap by straps passing through eyes at A, as shown. From the bar

H rises the curved loop-bar D, forming the loop or opening I, through which the driving-reins are passed, and by which they are prevented from falling off the back or hips of the horse when slack, and from being caught and dragged down by his tail. The arm B extends forward from the bar H, and is held down upon the strap E by a leather loop or otherwise, as may be preferred.

One or more additional loops or openings may be formed above the bar D, so as to give a greater elevation to the guide, or to form guides at different heights, if desired.

I claim—

The above-described rein-guide, consisting of the bars H and D and arm B, substantially as described.

LEMUEL RICHMOND.
